UNITED STATES PATENT OFFICE.

ROBERT C. STUBBS, OF DALLAS, TEXAS; MARIE M. STUBBS EXECUTRIX OF SAID R. C. STUBBS, DECEASED.

MACHINE FOR COMPACTING AND SOLIDIFYING CONCRETE AND OTHER PLASTICS.

Application filed November 30, 1925. Serial No. 72,335.

My invention relates to improvements in vibrating machines and more particularly to pressure vibrating machines for solidifying concrete and other plastics for making paving for streets, roads and the like; and the object is to provide compacting machines with means for effecting vibrations which can be transmitted to the mass to be solidified and particularly to provide means for varying the amount or force of the vibrations according to the requirements of different structures or for adjusting the mechanical devices for varying the force of the vibrations. For carrying out such objects a motor is provided with the necessary fly-wheels or balance wheels and a suitable frame. One object of this invention is to provide out-of-balancing devices which may be operated from one or more of the fly-wheels and to provide manually operated devices by which the speed of the out-of-balancing means may be increased or decreased at will and also to provide simple devices for changing the force of the vibrations. Another object is to transmit the vibrations created in the frame of the machine throughout the mass of material to be compacted and solidified. Other objects and advantages will be fully explained in the following description and the invention will be more particularly pointed out in the claims.

Similar characters of reference are used to indicate the same parts throughout the several views.

Fig. 1 is a perspective view of the vibrating machine.

Fig. 2 is a longitudinal section of two cylinders which are provided with light and heavy sides and also provided with adjusting devices for changing the position of one cylinder relative to each other.

Fig. 3 is an end elevation of the two cylinders, showing the two cylinders with their heavy sides diagonally opposite for causing the cylinders to balance so that there can be no out-of-balance effect.

Fig. 4 is a similar view, showing the outer cylinder shifted approximately 45 degrees relative to the inner cylinder which makes the cylinders partly out of balance.

Fig. 5 is a similar view, showing the outer cylinder shifted approximately 90 degrees relative to the inner cylinder for causing a greater out-of-balancing of the cylinders.

Fig. 6 is a detail view, showing the fly-wheels and the means for driving the out-of-balancing cylinders.

Similar characters of reference are used to indicate the same parts throughout the several views.

The drawings show a motor of approved type which is to be used for effecting vibrations of the mechanism herein shown. The motor is provided with fly-wheels 1 and 2 and a shaft 3 therefor. In the operation of the motor, the fly-wheels 1 and 2 are driven. Motion is obtained from one of the fly-wheels for operating the out-of-balancing elements. It is apparent that both fly-wheels can be used for this purpose. The shaft of the wheels is journaled in an upright frame 4. The motor, shown in this application, is provided with a crank case 5. The out-of-balancing elements are mounted on and operated by a shaft 6 which is journaled in frame 4. The out-of-balancing elements include an outer cylinder which has a heavy or weighted side 7 and a light side 8, each extending approximately 180 degrees. The two cylinders may be adjusted relative to each other so that there will be no vibrations or they may be adjusted so that the maximum vibrations may be obtained or adjusted to any point between the position for maximum vibrations and the position for no vibrations. The inner cylinder has a weighted side 9 and a light side 10. The inner cylinder may be keyed to the shaft 6 as shown in the drawings so that it will rotate with the shaft 6. The outer cylinder may be held at any required point of adjustment relative to the inner cylinder by a collar 11 which is rigid with the inner cylinder and is provided with a corrugated or notched periphery and by a dog or plunger 12 which is yieldably mounted on a spoke of the outer cylinder and adapted to engage any one of the corrugations or notches in the collar 11. The dog 12 is carried by a spring 13 which is attached to the spoke of the outer cylinder.

The means for driving the out-of-balance elements include a friction wheel 14 which is journaled in a yoke lever 15 which is carried by a fulcrum 16 which is mounted in the frame 4. The yoke 15 is used to hold the wheel 14 in mesh or against the face of the wheel 1 so that the wheel 14 will be driven by the wheel 1. The yoke 15 is provided

with a handle 18 for operation of the yoke and the wheel 14 for adjusting purposes. The friction wheel 14 is driven by the wheel 1 and drives the cylinder 7—8 or outer cylinder. The cylinders, that is, the inner cylinder and the outer cylinder are held in the balanced position normally by an involute spring 19 which is attached to the shaft 6 and to the rim of the outer cylinder. The 10 spring will yield for setting the cylinders in the required positions relative to each other. A brake shoe 20 is provided to bear against the periphery of the outer cylinder and this shoe may be used when the cylinders are to 15 be adjusted. Provision is made for axial adjustment of the friction wheel 14 on the fulcrum shaft 16 so that the speed may be increased or decreased by moving the wheel 14 so that it will engage the wheel 1 near 20 the periphery or to move wheel 14 nearer the center of the wheel 1 to decrease the speed.

The vibrations created by the inner and outer cylinders are transmitted to the frame 4 and from frame 4, the vibrations are transmitted through the rollers 21. The shafts 22 of the rollers 21 are journaled in bearings 23 which are rigid with the frame 4. The rollers 21 transmit the vibrations to the 30 transmitting unit which consists of a device in the nature of a platform composed of stringers 24 and cross strips or cleats 25. The stringers 24 and the cleats 25 are so arranged as to permit air and excess water and 35 mortar to escape from the surface of the concrete or plastic which is being treated with the pressure and vibrations.

It is common knowledge that concrete prepared for paving purposes require the addition 40 of enough water to make the mass workable and in this condition the concrete becomes a plastic or hydrostatic mass. The application of any amount of pressure will not eliminate the excess water from such 45 mass and unless eliminated, the space so occupied by the excess water and air will make voids in the seasoned mass. The device herein described affords pressure in combination with vibrations to a grid or device 50 placed on the surface of the plastic mass provided with openings for escape of air and excess water and mortar through the openings in the device which serves as a transmitting unit to transmit the vibrations created 55 in the frame to the mass of concrete while the transmitting unit remains in contact with the surface of the mass until the mass is sufficiently compacted and solidified.

A covering of hard crushed stone of suitable size is cast over the surface of the plastic mass before it is compacted and solidified and such stones are forced down into the mass and made a part of the mass by the devices herein described. Such stones occupy the spaces formerly occupied by the excess 60 mortar and water and air in the mass and are bonded to the concrete by the bonding elements which are crystallized upon their surfaces, resulting in producing an extremely 65 dense mass and becoming an approximately 70 integral body with the concrete.

What I claim, is,—

1. In a vibrating machine provided with a frame and a driven shaft and balance wheels thereon for compacting and solidifying plastic material; an out-of-balance element for creating vibrations in said frame, a friction wheel interposed between said out-of-balance element and said shaft and actuated by one of said wheels for operating said out-of-balance element, and a yoke fulcrumed on said frame for moving said friction wheel to contact with said balance wheel and said out-of-balance element.

2. In a vibrating machine provided with a frame and a driven shaft and balance wheels thereon for compacting and solidifying plastic material; an out-of-balance element for creating vibrations in said frame, a friction wheel interposed between said out-of-balance element and said shaft and adapted to be placed in contact with the face of one of said balance wheels and in contact with the periphery of said out-of-balance element, and a yoke fulcrumed on said frame for actuating said friction wheel to start and to stop the operation of said out-of-balance element.

3. In a vibrating machine provided with a frame and a driven shaft and balance wheels thereon for compacting and solidifying plastic material; an out-of-balance element for creating vibrations in said frame, a friction wheel interposed between said out-of-balance element and said shaft and adapted to be placed in contact with the face of one of said balance wheels and in contact with the periphery of said out-of-balance element, and a yoke fulcrumed on said frame for actuating said friction wheel to start and to stop the operation of said out-of-balance element, and means for shifting said yoke on its fulcrum for engaging said balance wheel closer to or further from its center.

In testimony whereof, I set my hand, this 18th day of November, 1925.

ROBERT C. STUBBS.
